(57) **CLAIM**

The ornamental design for a closet storage device, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a closet storage device showing our new design;

FIG. 2 is a front elevational view of the closet storage device of FIG. 1;

FIG. 3 is a rear elevational view of the closet storage device of FIG. 1;

FIG. 4 is a right side elevational view of the closet storage device of FIG. 1;

FIG. 5 is a left side elevational view of the closet storage device of FIG. 1;

FIG. 6 is a top plan view of the closet storage device of FIG. 1; and,

FIG. 7 is a bottom plan view of the closet storage device of FIG. 1.

The subject matter shown in broken lines forms no part of the claimed design.
